REMOVER AND INSERTER

Elbert Lee Ragland, Kermit, Tex., assignor of one-fourth to Frank Fletcher and one-fourth to Oby Lee Green, Kermit, Tex., and one-fourth to John Freudiger, Wink, Tex.

Application February 8, 1940, Serial No. 317,983

4 Claims. (Cl. 294—97)

This invention relates to a tool or device for pulling or removing and inserting pump liners. It is aimed to provide an exceedingly simple efficient, inexpensive and compact puller or tool, one which is self-adjusting so as to engage the liner with maximum advantage in order that maximum power may be applied so that the liner may be removed regardless of a tight fit or sticking, and a construction in which fouling will not result through adding pressure to the same when in operation.

The more specific objects and advantages will become apparent from a consideration of the following description taken in connection with accompanying drawings illustrating an operative embodiment.

In said drawings:

Figure 1 is a view of the puller in elevation;

Figure 2 is a fragmentary view of the puller in elevation, the same being shown in expanded condition to grip a liner;

Figure 3 is a substantially central vertical sectional view taken in the same plane as Figure 2;

Figure 4 is a vertical section taken on the line 25 4—4 of Figure 3;

Figure 5 is a horizontal section taken on the line 5—5 of Figure 3;

Figure 6 is a horizontal section taken on the line 6—6 of Figure 3;

Figure 7 is a plan view of the crosshead detached, and

Figure 8 is a detail section taken on the line 20 8—8 of Figure 3.

Referring specifically to the drawings wherein like reference characters designate like or similar parts, a central rod is provided at 10 which may have screw threads at 11 onto which an operating crosshead 12 may be screwed and which may also be engaged by a nut 13 abutting the crosshead or arm 12. At the other end, an enlarged bifurcated portion 14 is provided, a shoulder 15 resulting at the junction of the rod and bifurcated portion. In the bifurcation of said portion 14 which is designated 16, the inner ends of oppositely extending links 17 are disposed in overlapping relation and pins 18 extend through such links and bifurcated portion 14.

The outer ends of the links 17 are connected by pivot pins 19 to parallel gripping arms 20, the latter ends extending into enlarged slots at 21 in the gripping arms.

At the upper ends, gripping arms 20 are notched as at 22 and links 23, normally at the reverse angle to the links 17, extend into the 55 notches and are pivoted therein by pins 24.

Links 23 at the upper ends, by means of pins 25, are pivoted in notches 26 of a collar 27 whose movement in one direction is limited by abutment with the aforesaid shoulder 15.

The various pins at 18, 19, 24 and 25 may be 5 of any suitable construction but they preferably have eyes or openings through each end so as to removably receive cotters 28.

Contractile coil springs are employed at 29 which may be fastened to the uppermost pins 19 10 at their cotters 28 and to the lowermost pin 18 at a cottor thereof. However, when the springs 29 are more nearly in vertical position, as in Figure 1, they tend to draw the gripping arms 20 toward each other. 15

Attention is called to the fact, that the clearance provided by the slot 16 and slots 21 and 22 enable compact disposition of the parts and in fact the bars 20 and portion 14 to contact, with the collar 27, sliding away from the shoulder 15, 20 as in Figure 1.

Outwardly extending lugs or flanges 30 may be provided on the gripping bars 20 adjacent their lower ends.

In engaging a liner of an oil well pump or the like, to remove it, the device is inserted into the liner, one hand preferably engaging the collar 27 and the other hand engaging the rod 10 so that they may be moved relatively to facilitate insertion, following which the collar 27 is manually released and the springs 29 automatically position and expand the arms or bars 20 so that they grip the liner. Incidental to pulling the rod 10, it will be realized that such action tends to move the links 17 to the horizontal and to 35 bind them or tightly engage them with the liner.

The tool is useful not only as a puller in removing a liner but it is also useful in inserting a liner into the pump. In the latter use, the tool is reversed, with the crossbar 12 and nut 13 removed and the rod 10 inserted through the stuffing box which is originally occupied by the piston rod. This is advantageous since it is necessary to remove the piston rod and swab rubber assembly before removing a liner. The tool is 45 simply operated in the reverse manner to that for pulling, when inserting a liner.

Various changes may be resorted to provided they fall within the spirit and scope of the invention.

I claim as my invention:

1. A liner puller comprising a rod, a collar slidable on the rod, gripping members on opposite sides of the rod, links pivoted to the collar and to the gripping members, links pivoted to the 55

gripping members and to the rod, whereby the gripping members may contract and expand with respect to the rod, said rod and gripping members being slotted to receive the links so that the gripping members may be moved relatively close to the rod.

2. A liner puller comprising a rod having a shoulder, a collar slidable on the rod and engageable with the shoulder, gripping members on opposite sides of the rod, links pivoted to the collar and to the gripping members, links pivoted to the gripping members and to the rod, whereby the gripping members may contract and expand with respect to the rod, said rod and gripping members being slotted to receive the links so that the gripping members may be moved relatively close to the rod.

3. A liner puller comprising a rod, a collar slidable on the rod, gripping members on opposite sides of the rod, links pivoted to the collar

and to the gripping members, links pivoted to the gripping members and to the rod, whereby the gripping members may contract and expand with respect to the rod, the pivots for the links consisting of pins, cotters passing through the opposite end portions of the pins and contractile spring means fastened to certain of the cotters.

4. A liner puller comprising a rod having a shoulder, a collar slidable on the rod and engageable with the shoulder, gripping members on opposite sides of the rod, links pivoted to the collar and to the gripping members, links pivoted to the gripping members and to the rod, whereby the gripping members may contract and expand with respect to the rod, the pivots for the links consisting of pins, cotters passing through the opposite end portions of the pins, and springs in V relation fastened to certain of the cotters.

ELBERT LEE RAGLAND. 20
